CLAIM

The ornamental design for a diffuser for a vehicle oil filter as shown and described.

DESCRIPTION

FIG. 1 is top, front perspective view of the diffuser for a vehicle oil filter embodying our new design;

FIG. 2 is top, front perspective view of the diffuser for a vehicle oil filter of FIG. 1, with remaining components of the oil filter shown in broken lines;

FIG. 3 is left side elevational view of the diffuser for a vehicle oil filter of FIG. 1;

FIG. 4 is right side elevational view of the diffuser for a vehicle oil filter of FIG. 1;

FIG. 5 is front elevational view of the diffuser for a vehicle oil filter of FIG. 1;

FIG. 6 is rear elevational plan view of the diffuser for a vehicle oil filter of FIG. 1;

FIG. 7 is top plan view of the diffuser for a vehicle oil filter of FIG. 1; and,

FIG. 8 is bottom plan view of the diffuser for a vehicle oil filter of FIG. 1.

The broken lines are used to show a remainder of a vehicle oil filter for the purpose of illustrating environmental structure of the diffuser and form no part of the claimed design.
